UNITED STATES PATENT OFFICE.

OWEN W. ROBERTS, OF CHICAGO, ILLINOIS.

WASHING-MACHINE.

1,213,778.

Specification of Letters Patent. Patented Jan. 23, 1917.

Application filed April 10, 1914. Serial No. 830,872.

To all whom it may concern:

Be it known that I, OWEN W. ROBERTS, a citizen of the United States, residing in Chicago, in the county of Cook and State of Illinois, have invented a new and useful Improvement in Washing-Machines, of which the following is a specification.

This invention relates to improvements in washing machines.

10 An object of the invention is to provide a washing machine having a pivotally supported tub and so arranged that as the tub is rocked from said to side, the points of pivotal support shift in such a way that 15 the weight of the tub and contents will automatically serve to bring the tub to an easy stop at each end of the movements of oscillation.

The invention furthermore consists in the 20 parts and devices and in the novel combinations of the parts and devices herein shown, described or claimed.

In the drawing forming a part of this specification Figure 1 is a side elevation of 25 one form of washing machine embodying my improvements. Fig. 2 is an enlarged detail vertical section taken substantially on the line 2—2 of Fig. 1. Fig. 3 is part vertical section, part side elevation showing in 30 detail my improved form of pivotal support for the tub, the relative positions of the parts being the same as when the tub is at rest or in normal position, and Fig. 4 is a view similar to Fig. 3 but showing the relative positions of the parts when the tub is 35 near the end of one movement of an oscillation.

In said drawing, the supporting frame is shown as comprising two legs 10, 10 at each 40 end of the machine, only one set being shown in the drawing, each of said legs having its upper end received in and secured to a bracket 11, it being understood that the legs of the frame are suitably secured together 45 to form a sufficiently rigid support.

12 denotes the tub which is of substantially oval form in longitudinal cross-section and secured to each end of the tub is a bracket 13, which bracket 13, near its lower 50 end is provided with an outwardly extending pivot or pin 14 which is preferably slightly tapered as indicated at 15. Each bracket 13 is also provided with a rib 16 curved on its under side as shown at 17, the 55 rib being centered with respect to the pivot 14 and extending to either side thereof.

Each bracket 11 is provided with an upwardly extending lug 18 having a vertically elongated slot 19 and in which the pivot 14 projects and is adapted to move up 60 and down. To the rear of the lug 18, each bracket 11 is provided with a horizontal ledge or shoulder 20 which is directly under the inner end of the pivot 14 and the rib 16.

When the parts are in the position shown 65 in Figs. 1, 2 and 3, the pivots 14 will rest upon the ledge or shelf 20 and the points of support of the tub are in a vertical plane which passes through the center of weight 70 of the tub and its contents. As the tub is 75 rocked from side to side by any suitable means such as are commonly employed, the tub will be supported for a part of the time on the pivots 14 but as the oscillating movement is continued, the points of support will 80 be transferred from the pivots 14 to the ribs 16 and consequently the points of support will travel first to one side and then to the other side of said vertical plane and simultaneously therewith the pivots 14 will 85 be lifted within the slots 19 as shown for instance in Fig. 4.

From the preceding description it will be seen that as the tub approaches the limit of its rocking movement in either direction, the 85 points of pivotal support shift away from the line passing through the center of weight of the tub and its contents, which line corresponds to the section line 2—2 shown in Fig. 1. Consequently, the distance 90 between the center of weight and the points of pivotal support becomes automatically greater as the tub approaches the end of its oscillating movement so that the retarding force due to the weight of the tub and its 95 contents becomes automatically greater at the same time with the result that the movement of the tub is gradually reduced to zero without any severe shock on the parts. Having been brought to a stop, the 100 weight of the tub and contents naturally causes the tub to swing in the opposite direction and the above described operation again takes place at the end of the movement in the opposite direction. Stated in 105 another way, the pivotal connections are so designed that the more the tub is shifted from its normal position, the farther away the pivotal points of support move from the center of weight of the tub and contents. 110

In practice I have found that the arrangement which I have shown and described

gives extremely good results and jars and shocks on the machine such as have hitherto been an incident of most of the washing machines of the rocking tub type are minimized, thus increasing the life of the machine and without the necessity of using complicated devices or springs to reduce shock.

Although I have herein shown and described what I now consider the preferred embodiment of my improvements, yet it will be understood that various changes and modifications may be made without departing from the spirit of the invention, and all such changes and modifications are contemplated as come within the scope of the claims appended hereto.

I claim:

1. In a washing machine, a supporting frame having brackets at each end of the tub, a tub located between said brackets and having a bracket secured thereto on each end, each bracket on the frame having a horizontal ledge and each bracket on the tub having an outwardly extending pivot and a rib centered with respect thereto so

that as the tub is rocked from side to side, the points of support are transferred from said pivots to the ribs, said pivots serving to prevent slipping of the tub in either direction while supported on said ribs, substantially as specified.

2. In a washing machine, a supporting frame having brackets at each end of the tub, a tub located between said brackets and having a bracket secured thereto on each end, each bracket on the frame having a horizontal ledge and each bracket on the tub having an outwardly extending pivot and a rib centered with respect thereto so that as the tub is rocked from side to side, the points of support are transferred from said pivots to said ribs, said ribs being so constructed that the rocking movement of the tub imparts to said pivots a right line vertical movement, substantially as specified.

Signed this 2nd day of April, 1914, in the presence of two witnesses.

OWEN W. ROBERTS.
